UNITED STATES PATENT OFFICE.

WILLIAM M. STEVENSON, OF INDIAN ORCHARD, MASSACHUSETTS, ASSIGNOR
TO HODGES FIBER CARPET COMPANY, OF INDIAN ORCHARD, MASSA-
CHUSETTS, A CORPORATION OF MASSACHUSETTS.

PARTY-COLORED YARN AND MODE OF MAKING SAME.

No. 852,356.

Specification of Letters Patent.

Patented April 30, 1907.

Application filed January 29, 1907. Serial No. 354,717.

To all whom it may concern:

Be it known that I, WILLIAM M. STEVENSON, a citizen of the United States, residing at Indian Orchard, Massachusetts, have invented certain Improvements in Party-Colored Yarns and Mode of Making Same, of which the following is a specification.

My invention relates to the manufacture of fancy or party-colored yarns or threads composed of a plurality of strands, each consisting of a tape or ribbon of paper or like material, the object of my invention being to effect variety in the disposition of the colored strands in the twisted yarn, an object which I attain by causing one of a pair or group of strands to serve, in certain portions of the yarn, as a core around which the other strand or strands may be wrapped, thereby, in the case of a two-strand yarn, producing either party-colored portions or solid colored portions corresponding to either of the strands employed, and in the case of a three-strand yarn, producing combinations of either two or three colors, as may be desired.

In the accompanying drawing: Figure 1 is a view of a piece of two-strand yarn made in accordance with my invention; Fig. 2 is a similar view of a piece of three-strand yarn; Fig. 3 is a view, partly in elevation and partly in section, illustrating the essential features of one form of apparatus for producing a two-strand yarn in accordance with my invention; Fig. 4 is a side view of part of the same; Fig. 5 is a plan view of part of one of the elements of the device, and Fig. 6 is a view similar to part of Fig. 3, but illustrating a different relation of the parts from that shown in said figure.

The yarn shown in Fig. 1 is composed of two strands of different colors, say for instance, white and yellow, and in that portion of the yarn represented at *a* these colors appear alternately, while in that portion of the yarn represented at *b* the white strand only appears, and in that portion of the yarn shown at *c* the yellow strand only appears.

The three-strand yarn shown in Fig. 2 has a portion *d* in which the three strands, say white, yellow and green, appear; a portion *e* in which only the yellow and white strands appear; a portion *f* in which the green and white strands appear, and a portion *g* in which the green and yellow strands appear. Wherever a strand is removed from the sur-

face of the yarn it serves as a core, the other strand or strands being twisted around it so as to envelop it and hide it from view.

The disposition of the various strands in the finished yarn is dependent upon the relative degree of tension to which they are subjected before they reach the point at which they are twisted together, the strand to which tension is applied being caused to serve as the core strand.

In Fig. 3 of the drawing, 1 represents a spinning spindle having a flier 2, and 3 represents the spool or bobbin upon which the spun or twisted yarn or thread is wound. Above the spindle is a bracket 4 having a perforated lug 5 serving as a guide for the twisted yarn, the bracket also having, above said guide lug, a separator pin 6 disposed between the two ribbon-like strands *x* and *y* of which the yarn is to be composed, and other pins 7 which are engaged by the said strands so as to impart a certain degree of tension to each strand. Pivoted to the bracket 4 is a lever 9 which is susceptible of vibration whereby it may be caused to occupy a central or intermediate position, as shown in Fig. 3, or can be moved from said position either to the right or left. Projecting from the lever 9 is a plate 10 having therein an opening 11 contracted at each end, as shown at 12, in Fig. 5.

When the lever 9 occupies the central or intermediate position shown in Fig. 3 the tapes or ribbons *x* and *y* pass down through the enlarged central portion of the opening 11 in the plate 10, and are not affected by said plate, and, as each ribbon is under like tension, there is an even twist of the two ribbons and the resultant party-colored yarn, such as shown at *a* in Fig. 1. If, however, the lever 9 is moved to the left, as shown in Fig. 6, the ribbon *y* is caused to engage the contracted portion 12 at the right hand side of the opening 11 with the result that the tension upon said ribbon is increased, and this has the effect of causing the ribbon *x* to be lapped around the same so as to envelop and hide it, as shown in Fig. 6, and at *c* in Fig. 1, this result being aided by the fact that the ribbon *y* is partially folded by its engagement with the contracted portion 12 of the recess in the plate 10, thereby facilitating the infolding of the same by the other ribbon *x*. If the lever 9 is moved to the right the ribbon

x will be folded and subjected to increased tension, and it will be infolded by the ribbon *y*, thus producing the effect shown at *b* in Fig. 1.

5. In producing a three-strand yarn the three tapes or ribbons may be fed from equidistant points to the guide eye in the lug 5, and tension may be applied either directly to the ribbons or to the spools, bobbins or spindles 10 from which they are drawn, in order to determine the relative position of the strands in the completed yarn.

My invention is distinct from that method of producing yarns known as "plaiting" in 15 which a surface strand or strands is lapped around a core strand, first because of the ribbon-like character of the strands which I employ, and secondly because each of the strands in my improved yarn acts alternately as a 20 core strand and as a surface strand, whereby, in a given length of yarn in which all of the different effects have been produced, the strands will all be the same length, whereas in a "plaited" yarn in which the core strand 25 does not appear upon the surface the surface strand or strands are necessarily of much greater length than the core strand.

I claim:—

1. A twisted yarn composed of a plurality 30 of strands of ribbon form, said yarn having portions in which all of the strands appear upon the surface, alternating with portions in which one of the strands acts as a core and is enveloped by the other strand or strands.

35 2. A yarn composed of a plurality of strands of ribbon form, said yarn having portions in which the number of surface strands exceeds the number of such strands in the adjoining portions.

40 3. A yarn composed of a plurality of strands of ribbon form, each of such strands serving alternately as a core strand and as part of a party-colored portion of the yarn.

45 4. A yarn composed of a plurality of strands of ribbon form, each of such strands serving alternately as a core strand and as part of a party-colored portion of the yarn, all of the strands being of equal length in a given length of yarn.

5. A yarn composed of a plurality of 50 strands of ribbon form, said yarn having party-colored portions alternating with portions of solid color in which one strand is enveloped by the other.

6. A yarn composed of a plurality of 55 strands of ribbon form, said yarn having party-colored portions and portions of solid color corresponding to that of each of the strands, each of such latter portions having a core composed of the other strand. 60

7. The mode herein described of producing a composite and party-colored yarn, said mode consisting in twisting together a plurality of strands of ribbon form, and subjecting one of said strands, at intervals to greater 65 tension than that of the other strand or strands.

8. The mode herein described of producing a composite and party-colored yarn, said mode consisting in twisting together a plurality of strands of ribbon form, and subjecting each of the strands, in alternation, to a greater tension than that of the other strand or strands. 70

9. The mode herein described of producing a composite and party-colored yarn, said mode consisting in twisting together a plurality of strands of ribbon form, and imparting to each of the strands, in alternation, a partial fold before it reaches the point at 75 which the strands are twisted together.

10. The mode herein described of producing a composite and party-colored yarn, said mode consisting in twisting together a plurality of strands of ribbon form, imparting 85 to each of the strands, in alternation, a partial fold before it reaches the point at which the strands are twisted together, and, simultaneously with such folding of the strand, increasing the tension upon the same. 90

In testimony whereof, I have signed my name to this specification, in the presence of two subscribing witnesses.

WILLIAM M. STEVENSON.
